Primary Examiner — Mojtaba Tehrani(74) *Attorney, Agent, or Firm* — Banner & Witcoff, Ltd.(57) **CLAIM**

The ornamental design for an internal divider for a container, as shown and described.

DESCRIPTION

FIG. 1 is a front perspective view of an internal divider for a container showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depicting the remainder of the internal divider for a container form no part of the claimed design.
